UNITED STATES PATENT OFFICE

JOHN E. CARR, OF ATLANTA, GEORGIA

LOOSE-LEAF BINDER

Application filed February 19, 1929. Serial No. 341,206.

The present invention appertains to improvements in book binders and more especially to binders of the loose leaf type.

One of the most important objects of this invention is to provide a binder of such construction as to permit the insertion of a leaf between the leaves and index leaves already interposed between the clamping portions of the binder without necessitating the removal 10 of any of the leaves originally in place, and precludes the necessity of re-enforcing the index sheets on the binding margin.

Another object of paramount importance is the provision of a binder of such construction as to preclude the necessity of posts or of having the leaves punched in any manner.

Another object is to provide a binder including a frame which may be varied in capacity to accommodate loose leaf fillings 20 of varying thickness.

Still another object is to provide a binder in which the clamping means will not tend to deface the leaves retained thereby.

These and other objects of the invention 25 will become more apparent to the reader after considering the invention as described and claimed hereinafter.

Figure 1 is a top plan view of the improved binder.

Figure 2 is a side elevation of the improved binder.

Figure 3 is an end elevation of the book looking toward the binder.

Figure 4 represents a fragmentary longitudinal sectional view, taken substantially on the line 4-4 of Figure 3.

Figure 5 is a partial sectional view of a detail of the binder.

Figure 6 is an inside elevation of the adjustment means for the binder.

Figure 7 is a cross-sectional view, taken substantially on the line 7-7 of Figure 6.

Figure 8 is a longitudinal sectional view of one of the clamping elements employed on the binder.

Figure 9 is a side elevation of the tool employable for operating the clamp element shown in Figure 8.

Figure 10 is an enlarged side elevation of a

detail employed in conjunction with the adjustment means shown in Figure 6.

Figure 11 is a fragmentary side elevation looking toward the inner side of the adjustment means shown in Figure 6.

Referring to the drawings, wherein like numerals designate like parts, the invention includes the rectangular frame generally referred to by numeral 3. This frame includes a pair of elongated hollow side pieces 4-4 interconnected at their ends by detachable end pieces generally referred to by numerals 5-5, and a pair of intermediate connecting members 6-6 of substantially the same construction as the end pieces 5-5. The end pieces 5-5 and the connecting members 6-6 are each constructed of a pair of sections 7 and 8 respectively. The section 7 is provided for a substantial distance inwardly from one end with an undercut channel 9 for receiving the relatively narrow section 8, in a substantially dove-tailed connection. The grooved section 7 is provided with a key opening 10 having the notches 11 disposed in diametrically opposite directions. The inner surface of the channel 9 at the opening 10 is formed with a circular recess communicating with the notches 11, so that the wards 13 of the key 14 may be received in the recess and then turned to an offset position with respect to the aligned positions of the said notches so as to prohibit the accidental displacement of the key from its association with the sections 7 and 8. The stem of the key is provided with an extension 14' for disposition through a predetermined opening 15 in the section 8, so that these sections may be secured together in a predetermined extended position.

Each section is provided at its outer end with a laterally disposed head 15 having a pocket 16 therein, in which a spring-projected ball 17 is seated, and adapted to partially project beyond the upper surface of the head. The upper and lower side pieces 4-4 are open at their ends and provided with openings 18, in their side and end walls through which the heads 15, may be inserted in the side pieces from the rear and each side piece is formed in its outer wall opposite each open-

ing 18 with an aperture 19, for receiving one of the spring-pressed balls 17, which are adapted to engage in the opening 19 of the hollow side pieces 4 to retain the sections connected to the frame.

5 The upper side piece 4 is provided with a pair of internally threaded tubes 20—20 disposed therethrough and suitably secured by welding or otherwise.

10 A clamp member such as is shown in Figure 8 of the drawings is threadedly engaged through each tube 20. These clamp members each consist in construction of an externally threaded body 21 provided at one end with a socket 22 of polygonal cross section. The opposite end of the body has a reduced extension 23, to which a cap 24 is swivelly connected.

15 In Figure 9 a tool is shown in the form of a bar 25, of polygonal shape and having one end portion bent laterally to provide a handle 26. This tool is engageable at one end within the socket 22, for feeding the body 21 inwardly so that the swivelled cap 24 may be 20 engaged against the sheets, to firmly compress the same within the frame 3.

25 A pair of cover sections 27—27 of any suitable construction and material are hingedly connected to the side pieces 4—4 of the frame 3 at the point designated by numeral 28.

30 In the manufacture of this novel book construction, let it be understood that various changes may be made in the shape, size and materials without departing from the spirit 35 and scope of the invention as claimed hereinafter.

Having described the invention, what is claimed as new is:

1. A book structure comprising a substantially rectangular binder frame for receiving one end portion of a loose leaf filling said frames including side pieces, clamp means on said frame for engagement with said end portion of the filling, and means for varying the width of the frame, said means consisting of a pair of detachable end pieces, said end pieces being each divided into a pair of sections, a lateral head for one end of each section for engagement with one end of one of the frame side pieces, and means for adjustably connecting the other end portions of the complementary sections together.

2. A book structure comprising a substantially rectangular binder frame for receiving one end portion of a loose leaf filling said frames including side pieces, clamp means on said frame for engagement with said end portion of the filling, and means for varying the width of the frame, said means consisting of a pair of detachable end pieces, said end pieces being each divided into a pair of sections, a lateral head for one end of each section for engagement with one end of one of the frame side pieces, a dove-tailed slidable con-

nection between said sections, and a detent for securing the sections in adjusted positions.

3. A book structure comprising a substantially rectangular binder frame for receiving one end portion of a loose leaf filling said frame including side pieces, clamp means on said frame for engagement with said end portion of the filling, and means for varying the width of the frame, said means consisting of a pair of detachable end pieces, said end pieces being each divided into a pair of sections, a lateral head for one end of each section for engagement with one end of one of the frame side pieces, a dove-tailed slidable connection between said sections and a detent for securing the sections in adjusted position, said sections being provided with key slots, and a key for disposition through certain registered slots in the sections for retaining the sections in a predetermined extended position.

4. A book structure comprising a substantially rectangular binder frame for receiving one end portion of a loose leaf filling said frames including side pieces, clamp means on said frame for engagement with said end portion of the filling, and means for varying the width of the frame, said means consisting of a pair of detachable end pieces, said end pieces being each divided into a pair of sections, a lateral head for one end of each section for engagement with one end of one of the frame side pieces, a dove-tailed slidable connection between said sections and a detent for securing the sections in adjusted position, said sections being provided with key slots, and a key for disposition through certain registered slots in the sections for retaining the sections in a predetermined extended position, and tensional means for retaining said heads in engagement with said frame.

In testimony whereof I affix my signature.

JOHN E. CARR.
